RUBBER HEEL

Frank P. Wright, Long Beach, Calif.

Application September 4, 1934, Serial No. 742,599

1 Claim. (Cl. 36—75)

My invention relates to the shoe industry, and particularly to rubber heels for use on shoes of various kinds.

One of the drawbacks of rubber heels is that they become readily worn on the lower face thereof and particularly at the rear of the heel.

It is an object of my invention to provide a rubber heel which will be so reinforced as to substantially lengthen the life of the heel by preventing the quick wearing of the heel at the rear edge thereof.

The manner of accomplishing the foregoing object as well as further objects and advantages will be made manifest in the following description taken in connection with the accompanying drawing, in which:

Fig. 1 is a bottom plan view of the preferred embodiment of the heel of my invention.

Fig. 2 is a vertical sectional view taken on the line 2—2 of Fig. 1.

Fig. 3 is a view similar to Fig. 2 illustrating the heel of my invention applied to a shoe.

Fig. 4 is a perspective view of the reinforcing member of my invention.

Fig. 5 is a rear view of the heel shown in Fig. 1 mounted on a shoe.

Referring specifically to the drawing, the rubber heel 10 of my invention is shown as including a body of rubber 11 of the usual shape, this body having a number of nail holes 12 formed therein, each of these holes having a washer 13 embedded in the rubber body 11 around the hole adjacent its lower end. Also formed in the rubber body 11 are nail holes 14. Surrounding each of the holes 14 is one of a pair of ears 15 which are shaped identically like the washers 13, but which are embodied in a reinforcing member 16 including an arcuate plate 17 provided with legs 18 which integrally connect the plate 17 with the washer-like ears 15.

Permanently secured upon the lower or wearing face 19 of the plate 17 is a facing 20 of extremely hard material such as tungsten carbide or the like. The heels 10 are preferably in right and left styles, the heel as shown being for a left shoe as the reinforcing members 16 are preferably located on the rear outer edge of the heel.

In the manufacture of the rubber heel 10 the washers 13 and the reinforcing member 16 are all held in place in the mold by suitable fixtures on the mold and the rubber forced around these elements so as to fill the mold. This results in the washers 13 being embedded deep in the rubber and the reinforcing member 16 is also embedded

therein excepting that the plate 17 and its facing 20 are disclosed at the rear edge of the heel as clearly shown in Fig. 1.

In applying the rubber heel 10 to the shoe 25 as shown in Fig. 3 suitable nails 26 are driven into the holes 12 and 14 so as to pass through the washers 13 and ears 15 and into the sole of the shoe 25. The heel 10 is thus securely fastened to the shoe and the member 16 is at the same time anchored by the nails 26 to the shoe.

In using the heel 10 of my invention it is found that although the member 16 is formed of metal no noise is caused by walking on this heel. This is believed to result from the fact that the member is cushioned from the shoe 25 on which the heel is shown applied in Figs. 3 and 5 by a considerable portion of the rubber body 11 which is disposed between the member 16 and the shoe 25.

It is thus seen that I have produced a rubber heel which will have a much longer life than rubber heels in general use yet without reducing in any way the quietness given to walking by the use of rubber heels.

While I have shown and described but a single embodiment of my invention, it is to be understood that various changes may be made in this without departing from the spirit of the invention or the scope of the appended claims.

An important advantage of the rubber heel of my invention which also should be pointed out is the protection of the heel from wearing by the member 16 without diminishing the resiliency of the heel itself. It is of course evident that the member 16 by protecting the rear edge of the heel insures that the original resiliency of the rubber heel will be maintained until the member 16 has been worn away, thus greatly increasing the effective life of the heel.

What I claim is:

In a rubber heel the combination of: a rubber heel body, having an upper attaching face and a lower wearing face, and nail holes formed in said wearing face spaced inwardly substantially equal distances from the outer edge of said body; washers embedded in said body about said nail holes; a block of metal embedded in said body to conform with a portion of the rear outer edge of said body to one side of the center of said body and having its lowermost surface lying in the plane of said wearing face, said block at its ends overlapping an adjacent pair of said washers; and means for connecting said block to said washers.

FRANK P. WRIGHT.
